(Cl. D71—1)

FIG.1.

FIG.2.

FIG.3.

FIG.4.

To all whom it may concern:

Be it known that I, Armand J. Thieblot, a citizen of the United States and a resident of Hagerstown, county of Washington, and State of Maryland, have invented a new, original, and ornamental Design for an Airplane, of which the following is a specification, reference being had to the accompanying drawings, forming a part thereof.

Figure 1 of the drawings is a plan view of the airplane embodying the new design;

Fig. 2 is a side elevation of the airplane;

Fig. 3 is a perspective view of the airplane as it would appear from a point off to the side and slightly forward and above the airplane while in flight; and

Fig. 4 is a front elevation of the airplane.

I claim:

The ornamental design for an airplane, substantially as shown.
